[57] CLAIM

The ornamental design for a temperature sensor, as shown and described.

DESCRIPTION

FIG. 1 is a top view illustrating a first embodiment of a new design for a temperature sensor;

FIG. 2 is a side view thereof, the opposite side view being substantially similar while the top plan view is identical to that shown in FIG. 1;

FIG. 3 is a side view of a second embodiment of a new design for a temperature sensor while the top plan view is identical to that shown in FIG. 1;

FIG. 4 is a perspective view illustrating a third embodiment of our new design. The broken line showing of tube or pipe is for illustrative purposes only and forms no part of the claimed design;

FIG. 5 is a top elevational view of the third embodiment of our new design; and

FIG. 6 is a side view of the third embodiment of our new design.
